UNITED STATES PATENT OFFICE.

FLORENCE J. GAULT, OF CINCINNATI, OHIO.

CROCHET-THREAD HOLDER.

1,097,421.

Specification of Letters Patent.

Patented May 19, 1914.

Application filed June 12, 1912. Serial No. 703,210.

To all whom it may concern:

Be it known that I, FLORENCE J. GAULT, a citizen of the United States, residing at Cincinnati, in the county of Hamilton and 5 State of Ohio, have invented certain new and useful Improvements in Crochet-Thread Holders, of which the following is a specification.

My invention relates to holders for balls 10 of wool, silk, linen, cotton or other thread to be formed into fabric by a crochet needle.

In the art of crocheting women are often hindered due to the fact that the spool or ball of crochet thread being light in weight 15 often becomes dislodged from the lap and falls upon the floor, thereby entangling the thread and often necessitating the loss of a great deal of time to re-adjust the same.

The object of my invention is to provide 20 a reel adapted to carry a spool or ball of crochet thread, said reel having fastening means thereon for attaching it to the clothing of the person in order that it may be retained in a convenient position at all 25 times, thus eliminating the liability of it becoming entangled by falling upon the floor or becoming entangled in the clothing of the person.

My invention comprises a frame, one side 30 of which is adapted to be opened to form a spring bar adapted to carry a spool or ball of crochet thread, means on the other side of said frame for suspending said frame, a ring on said frame, and means whereby the 35 ball of thread is caused to unwind gradually without becoming entangled.

In the accompanying sheet of drawing, which serves to illustrate my invention: Figure 1 is a perspective view of my device 40 with a ball of crochet thread mounted thereon; Fig. 2 is a view of my improved frame showing the fastening means open and also the spring bar ready to have a spool inserted therein; Fig. 3 is a view of a ball of 45 crochet thread with my improved attachment thereon for preventing the thread from unwinding faster than is necessary; Fig. 4 is a detail perspective view of one of the sleeves employed in Fig. 3; and Fig. 5 50 is a detail perspective view of part of the fastening means shown in Figs. 1 and 2.

In the embodiment of my invention as 55 illustrated, and which shows a preferred construction, 1 represents a wire frame preferably rectangular in shape, as illustrated, and adapted to be opened at 2, the

lower side thereby constituting a bar 3 upon which a spool or ball of crochet thread is adapted to rest as shown in Fig. 1. The wire frame is twisted or double coiled at 5 60 in order that the bar 3 is normally held out of engagement with the rest of the frame as shown in Fig. 2. When the frame is closed the free end of the bar 3 rests in the hook 6 on the end of the frame. The hook 6 65 is preferably formed, as clearly shown in Fig. 1, in the shape of a shepherd's crook being bulged inwardly near the end to form a spring catch to securely hold the end of the bar 3 within the hook. Said hook also 70 extends away from the frame at its free end to permit the bar 3 to more readily enter the hook. In order to form a fastening means for suspending the frame I provide 75 preferably a pin as shown in Figs. 1 and 2 fastened tightly upon that part of the frame which is opposite the bar 3. This fastening means consists of a pin 7 similar in construction to the ordinary safety pin, the pin being fastened to the frame by means of 80 a sleeve 8 which binds the back of the pin to the frame and may be permanently fastened thereto. The point or free end of said pin is adapted to fit in the box shaped receptacle 9 made of spring steel which has a 85 slot 9' in the bottom thereof as shown in Fig. 5. This slot is in the central portion of the bottom of said box so as to render the pin less liable to become unfastened as is so often the disadvantage with the safety 90 pins of the ordinary type.

Mounted on the sleeve 8 is a ring or eyelet 10 through which the thread coming from the ball or spool passes thereby limiting the pull to one direction on the spool or 95 ball of crochet thread and thereby eliminate any liability of the thread becoming entangled. Owing to the fact that balls of thread 14 are wound in a peculiar manner by machinery so as to cause a complete 100 strand or loop to unwind at a time, the thread becomes entangled because too much has been unwound. In other words the thread does not unwind gradually as it does 105 from a spool but when the thread is drawn in unwinding a complete loop and sometimes more unwinds from the ball. This very often causes the thread to tangle and interferes with the progress of the person in crocheting. To eliminate this disadvantage 110 in the ball of crochet thread so as to apply it successfully to my improved frame, I pro-

vide telescopic flanged members 11 to fit into either side of the ball of crochet thread. The cylindrical portions of these flanged members are split at 13 and are preferably made of thin spring steel so that one can be squeezed together a trifle to fit into the other, and each is provided with a flat flange 12. When these flanged members are placed in the ball of thread they can be telescoped one with the other so as to allow the flanges of said members to engage the sides of the ball of thread, then the ball with the flanged members mounted therein is placed upon the spring bar 3 of the frame and the bar is then inserted in the catch or hook 6. Now when the thread is unwound from the ball, the thread will not unwind a complete loop from around the ball but will only unwind from one side to the other due to the slight friction between the flanges and the sides of the ball of thread. It will be understood that this friction is not great enough to cause any exertion upon the part of the operator to unwind while using the thread. Furthermore, if the flanged members were not used the thread would tend to entangle itself with the twisted portion 5 of the frame.

Thus by the use of my invention a woman can suspend the crochet thread frame from her belt or clothing and need have no fear of the thread becoming entangled or rolling upon the floor and can stand up and move around at her pleasure without having to pick up the crochet thread each time.

Modifications of my invention may be made without departing from its spirit or

scope, and I do not wish to be confined to the exact details shown.

What I claim as new and desire to secure by Letters Patent is:

1. In a crochet thread holder, a rectangular spring wire frame, means for attaching same to the clothing of the user, an adjustable separable spool detachably, loosely and rotatably mounted upon said frame, a ring in said frame opposite said spool hold adapted to receive the thread from the spool and to be freely and easily unwound therefrom through said ring, substantially as set forth and for the purposes specified.

2. In a crochet thread holder, a pair of cylindrical telescoping members each longitudinally slotted and each having a flat flange upon one end thereof to form when interengaged an adjustable spool to receive hollow balls of yarn or thread of varying widths, and a frame adapted to carry said spool and upon which said spool is loosely, rotatably and detachably mounted, substantially as set forth and for the purposes specified.

3. In a holder for crochet thread, a rectangular spring wire frame, means for detachably securing same to the clothing of the user, a separable spool holder, and means for loosely mounting said spool upon said rectangular frame, substantially as set forth and for the purposes specified.

FLORENCE J. GAULT.
